(57) **CLAIM**

The ornamental design for a drying mat with erectable pegs, as shown and described.

DESCRIPTION

FIG. 1 is a perspective view of the drying mat with erectable pegs with the pegs shown in a stowed position;

FIG. 2 is a perspective exploded view thereof;

FIG. 3 is a perspective view with the pegs positioned for use;

FIG. 4 is a side elevation view with the pegs shown in top plan exploded view;

FIG. 5 is a top plan with pegs in a stowed position;

FIG. 6 is a side elevation exploded view;

FIG. 7 is an end elevation view; and,

FIG. 8 is a bottom plan exploded view.

The portion of the figures shown in broken lines is for the purpose of showing the environment in which the design may be seen and forms no part of the claimed design.
